THERMIONIC FILAMENT OF VARIABLE CAPACITY

Erwin F. Lowry, Wilkinsburg, Pa., assignor to Westinghouse Electric & Manufacturing Company, East Pittsburgh, Pa., a corporation of Pennsylvania

Application March 15, 1934, Serial No. 715,644

2 Claims. (Cl. 250—27.5)

This invention relates to electron discharge devices and especially to such a device having a cathode of variable capacity.

It is an object of my invention to provide an electron discharge device having a main cathode section for normal operation of the tube and having an auxiliary or booster electron emitting portion that will operate when peak current load is necessary in the electrode output circuit.

Another object of my invention is to provide an electron discharge device and circuit therefor in which considerable input power is saved by having one portion of the cathode operating for low output demands and another portion of the cathode being operated when the demand is at peak load.

Other objects of the invention will become more apparent from an examination of the drawing, in which the figure is a view, partially in cross-section and partially diagrammatic, of an electron discharge device and its circuit embodying the invention.

In hot cathode tubes of the present art and especially in gas filled tubes having an oxide coated cathode, the plate currents which may be drawn from the tube are considerably below the thermionic emission of the cathode. This limitation is necessary for the reason that the rate of disintegration of the coating material is a function of the space or discharge current density on the cathode surface. An oxide cathode that will operate satisfactorily for 10,000 hours at a drain rate of 3 amperes per square inch of cathode surface has an emission of at least 10 amperes per square inch of cathode surface. But if this cathode is run at 5 amperes per square inch of cathode surface, its useful life may be as low as 1200 hours. As a result, the filaments for gas filled tubes are designed to operate at 3 amperes per square inch of cathode surface or less in order that the tube may have a satisfactory life.

These tubes are operated at much less than their peak rating during a considerable portion of their useful life. Quite a number of these tubes are used in a circuit in which their cathodes are heated for over a considerable standby period, in order that they may operate for a short time at peak load. Other tubes are operated most of the time at values much less than their peak load. Nevertheless, the filaments must be of such size that their peak rating is not to exceed 3 amperes per square inch, and this requirement of size necessitates a correspondingly large power input to operate them at the proper temperature.

I have invented a new and useful type of filament for cathode structure for such tubes which will materially reduce the input power required during that part of the tube's operation when current drains are less than the peak plate current rating. My invention is embodied in the specific form disclosed in the drawing, but is not limited to the specific details disclosed therein.

The electron discharge tube 10 comprises the usual air-tight envelope 11 having the anode 12 and cathode 13 therein. If desired, other electrodes auxiliary to these main electrodes may be placed therein. The cathode structure preferably comprises a section 14. This section 14 has connections 15 and 16 to terminals 17 and 18 to which a heating means for the cathode can be connected. This heating means may, of course, be the usual transformer connection 19 to a supply circuit of suitable rating.

The anode 12, which may be of any suitable size and shape, has an external connection 20 connected to the external load circuit 21. A suitable input means may be provided such as the circuit 22 through the transformer 23 to this external anode circuit. The return anode circuit 25 lead 28 is connected to a terminal 29 connected in turn to an auxiliary or booster filament portion 24 that is preferably connected to a common point 25 which divides the main filament section 14 into two portions 26 and 27.

While my invention in its broadest aspect is not limited to any specific shape or size of the electrodes, I prefer to make the filament portions in the spiral corrugated ribbon form disclosed in the drawing and more specifically described in my co-pending application Serial No. 612,505 for a high efficiency oxide coated cathode method of manufacture filed May 20, 1932. This ribbon is preferably formed of the nickel-cobalt iron-titanium alloy described therein and is coated with the standard coating of barium and strontium oxides.

The operation of my device is as follows: The tube may be required to have a peak plate current rating of 5 amperes, for example, but may only be required to supply a continuous current of 3 amperes or less for the major portion of its life. The section 14 is accordingly designed to furnish this continuous usual demand of 3 amperes. By designing this filament section 14 and the current through the transformer 19 to provide these 3 amperes of current by the electron emission from this main portion 14 of the cathode assembly, this anode current of 3 amperes or less returns to the cathode through the auxiliary cathode portion 24. This auxiliary portion 24 has

a relatively high temperature coefficient of resistance, so that the filament section 24 is comparatively cool during the operation at this low current of 3 amperes. When the plate current 5 passes the 3 ampere demand, the filament section 24 is designed to reach a temperature at which appreciable electron emission is obtained, and when 4 amperes is flowing in this external anode circuit, the electron emitting portion 24 10 will reach full operating temperature of approximately 900° C.

The additional electrons to increase the anode current from 3 amperes to 5 amperes will be largely drawn from the auxiliary or booster portion 15 24 of the cathode assembly, and this additional drain will not adversely affect the life of the main portion 14 of the cathode. This additional supply of electrons is automatically brought into operation by the heating of the cathode section 24 by the increased anode return current.

When the external anode circuit decreases its current to below 3 amperes, for example, the auxiliary filament portion 24 will cool and absorb very little of the input energy. Considerable 25 economy will accordingly be effected when the tube is operating below its peak rating or is in a standby position.

The invention is not limited to filaments for gas filled tubes, but may be found very useful

for high vacuum tubes. In gas filled devices the voltage drop in this type of filament may be limited to about 5 volts, but in high vacuum tubes it may be as much as 20 or 25 volts without causing difficulty in operation.

It will be obvious to those skilled in the art that many other forms of my invention exist and the only limitations thereon are those necessitated by the prior art or imposed by the following claims.

I claim as my invention:

1. A cathode assembly comprising two connections for heating current, electron-emitting portions between said two connections, a connection for return of the anode current and an auxiliary electron-emitting portion between said last-mentioned connection and the first-mentioned electron-emitting portions, the emissivity of the auxiliary portion varying directly in substantial amounts with the anode current.

2. A cathode assembly comprising two electron emitting portions, one of said portions being electron emitting in response to a heating current provided therefor, the other portion being electron emitting in response to the load current, the emissivity of said last-mentioned portion varying in substantial amounts with the load current.

ERWIN F. LOWRY.
